(57) **CLAIM**

The ornamental design for a reticle, as shown and described.

DESCRIPTION

FIG. 1 is a front view of a reticle showing my new design at a first magnification;

FIG. 2 is another front view of the reticle at a second magnification higher than the first magnification;

FIG. 3 is another front view of the reticle at a third magnification higher than the second magnification shown in a use configuration with an optical medium of a firearm optical sight;

FIG. 4 is another front view thereof shown in another use configuration with an optical medium of a firearm optical sight; and,

FIG. 5 is a perspective view of a firearm optical sight. The broken lines depict portions of the optical medium and environmental structure of a firearm optical sight that form no part of the claimed design.
